[57] CLAIM

The ornamental design for a switch extension, as shown and described.

DESCRIPTION

FIG. 1 is an environmental perspective view of a switch extension showing our new design;

FIG. 2 is a front elevational view thereof;

FIG. 3 is a rear elevational view thereof;

FIG. 4 is a top view thereof;

FIG. 5 is a right side elevational view with the left side being a mirror image thereof; and,

FIG. 6 is a bottom view thereof.

The broken line showing of the switch plate illustrated in FIG. 1 and the wall and extension guide illustrated in FIGS. 1 and 4 is for illustrative purposes only and forms no part of the claimed design.

The break in the extension rod illustrated in FIGS. 2, 3, and 4 indicates indefinite length.

FIG. 1
